UNITED STATES PATENT OFFICE.

WILLARD C. JAMES, OF LOS ANGELES, CALIFORNIA.

FOLDING BED.

No. 831,227.

Specification of Letters Patent.

Patented Sept. 18, 1906.

Application filed December 19, 1904. Serial No. 237,359.

To all whom it may concern:

Be it known that I, WILLARD C. JAMES, a citizen of the United States, residing at Los Angeles, in the county of Los Angeles and State of California, have invented new and useful Improvements in Folding Beds, of which the following is a specification.

The main object of this invention is to provide a folding bed having a panel front and in which the mattress-carrying member of the bed will be supported in such manner as to provide for thorough ventilation and facilitate cleaning.

Another object of the present invention is to provide in connection with a folding bed improved means for automatic closure of the opening left by the folding bed when lowered.

A further object of the invention is to improve the construction of the folding bed with a view to cheapness, lightness, and better appearance.

The accompanying drawings illustrate the invention.

Figure 1 is a front elevation of the bed in closed position. Fig. 2 is a vertical section on line $x^2 x^2$ in Fig. 1. Fig. 3 is a vertical section showing the bed lowered. Fig. 4 is a rear elevation of the lower part of the device in closed position.

The form of bed here shown is particularly intended for use as a fixture in an apartment, the bed folding into a recess in the wall of said apartment; but in some respects the invention is not limited to such an application thereof.

1 designates a part of a wall of such an apartment, and 2 a recess therein. The bed (indicated at 3) is mounted or supported in such manner as to fold up in such recess or 40 to be lowered to position for use. For this purpose the bed may be supported on a pivotal supporting member 4, placed near to and adapted to support the head thereof, having two arms or legs 5 6, extending preferably at 45 right angles to one another, the arm 5 always resting at its lower end on the floor (indicated at 7) and the arm 6 normally extending horizontally outward to serve as a shelf or seat when the bed is in closed position, but turning down to rest on the floor, as hereinafter described, when the bed is lowered.

The bed 3 is mounted on the pivotal supporting member 4 by a joint or connection (indicated at 8) which enables the bed to have 55 a pivotal or turning movement on said sup-

porting member. This movement is limited in one direction by stop means (indicated at 9) on the bed engaging with the arm 5 of the supporting member 4, and such movement is limited in the other direction by projections 10 on the bed engaging with the floor 7 when the bed is lowered to support the bed in horizontal position, said projections 10 being preferably constructed to serve as shelves when the bed is in raised position. A mirror 11 may be formed on the front or bottom 16 of the bed between the shelves 10.

The pivotal supporting member 4 may have hooks, pins, or claws 12 engaging in sockets 13 in the floor to hold the bed in definite position. The pivotal connection between the bed and this support may consist of hooks or claws 14, engaging in slots or sockets 15 in said support.

When the bed is in raised position, the under or front portion 16 thereof, together with the portion 5 of member 4, forms a complete closure for the recess 2, said parts 16 and 5 being under these conditions substantially continuous or in one plane. When the bed is lowered, it is turned down and away from said recess, and it is desirable to provide closure means for closing or concealing the recess. Said closure means may consist of a plate 17, supported in the recess 2 by means of vertically-swinging pivotal bars or links 18, which are pivoted at 19 at their lower ends to the casing 1 at each side of the front of the recess and are pivoted at 20 at their upper ends to lugs or brackets 21, extending rearwardly from the plate 17. The tendency of this closure-plate 17 is to swing under the influence of gravity down and rearwardly to position shown in Fig. 2, with the legs or extensions 22 at the lower end thereof resting on the floor 7 of the recess. Means are provided on the bed 3 for engagement with this closure-plate to lift it upwardly and forwardly when the bed is lowered, said means consisting of arms 23 on the bed extending in position to engage under said plate.

The head of the bed is preferably provided with a board or cross-piece 24, which when the bed is in lowered position comes directly under the bottom of the plate 17, so as to form substantially a continuation thereof as regards appearance and closure of the recess.

While the above-described general construction of the bed is adaptable for various designs of bed, it is herein shown as applied in

connection with a construction of bed which will have the appearance and general advantages of an iron or metal bedstead, the upper or main members of the bed-frame consisting of iron stringer-bars 26 and cross-bars 27, preferably tubular, the foot corner-posts 28 and head corner-posts 29 also preferably tubular, these tubular elements being connected at the corners by iron fittings 30.

- 10 The front member or bottom 16 of the bed-frame is connected to the frame-bars 26 by brackets 31 on said front member, to which said bars are secured by screws 32. Braces 33 34, connecting the front member 16 with the frame-bars 26 and connecting said frame-bars with the head corner-posts 29, are provided, and the foot of the bed is provided with the usual metallic bars 35 of any usual or suitable construction in the manner of the ordinary metal bed. As far as the frame itself is concerned the bed so constructed is substantially a metal bed and has all the advantages thereof. In order, however, that the head of the bed shall conform in design to the main body of the bed and carry out fully the similarity to a metal bed, a metallic sectional head-piece (indicated at 36) may be provided on the closure-plate 17, said head-piece being formed of metal bars with side posts 37, extending upwardly in line with the corner-posts 29 to form apparently a continuation thereof, and cross-bars or metal work connecting the same in any usual manner, according to the design of head-piece preferred.
- 35 The upper end of the posts 29 and the lower end of posts 37 are preferably beveled, as shown at 38, to more effectually conceal the joint.

When the bed is closed, the closure 17 will rest on floor 7, as shown in Fig. 2, and the bed will rest on the pivotal support member 5, which always bears at its lower end on the floor. The arms 23 may also rest on the floor, holding the bed in vertical position.

- 45 When the bed is to be lowered, it is pulled outwardly, turning with the support member 5, which turns on its lower end until the support member 6 strikes the floor, whereby its motion will be arrested, and further pivotal movement of the bed will be by turning on the support at 8 until the legs 10 come to rest on the floor. In this lowering of the bed the initial movement will be free—that is, it will be resisted only by the preponderance of 55 weight of the bed to the rear of pivotal support 5, but after a definite movement arms 23 will engage the closure 17, and the latter will act as a partial counterbalance, resisting further movement, so as to ease off the descent 60 of the bed and at the same time raising the closure to a closed position.

A plate or strip 40 is secured to member 5 to form a retaining-ledge for engaging the front or panel plate 16 when the bed is raised.

65 It will be seen that the mattress-carrying

panel, consisting of members 26-27 of the bed, is held apart from the front panel members 16 in such manner that when the bed is raised, as shown in Fig. 2, there will be a space left between the mattress and the front for the sake of ventilation and cleanliness.

It will also be noted that the bed is supported by pivots at 12 13, located outside of the opening or recess into which the bed folds. This is of advantage, as it obviates mutilation or cutting away of the front of the bed.

What I claim is—

1. A folding bed comprising a pivotal support mounted to turn on its lower end and provided with means to arrest its pivotal movement, and a bed-frame pivotally mounted on said pivotal support, in combination with a casing having a recess for containing the folding bed, and a closure for said casing operated by movement of the bed, said closure being mounted to move rearwardly and downwardly in the casing and having portions to rest on the floor of the casing, and the bed having means extending under the closure to lift the same.

2. A folding bed comprising a pivotal support mounted to turn on its lower end and provided with means to arrest its pivotal movement, and a bed-frame pivotally mounted on said pivotal support, in combination with a casing having a recess for containing the folding bed, and a closure for said casing operated by movement of the bed, said closure being mounted to move rearwardly and downwardly in the casing and having portions to rest on the floor of the casing, and the bed having means extending under the closure to lift the same after a definite movement of the bed.

3. A folding bed comprising a bed-frame having upper and lower members, a pivotal support for the lower member mounted to turn on its lower end and provided with means to arrest its pivotal movement, the lower member of the bed-frame being pivotally connected to said pivotal support to turn thereon, and the upper part of the bed-frame extending rearwardly from the lower member and having a downward extension to engage the pivotal support to limit the relative pivotal movement of the bed and support.

4. A casing having a recess, a bed adapted to fold into said recess, and a closure-plate for concealing the recess when the bed is down, said plate having links swinging in a vertical plane pivoted to the upper portion thereof at one end and pivoted near the front of said recess at the other end, said links adapted to swing the plate into closed position.

5. A casing having a recess, a bed adapted to fold into said recess, and a closure-plate for concealing the recess when the bed is down, said plate having links swinging in a

vertical plane pivoted to the upper portion thereof at one end and pivoted near the front of said recess at the other end, said links adapted to swing the plate into closed position, the bed having means extending under the closure-plate to lift the same when the bed is lowered.

In testimony whereof I have hereunto set my hand, at Los Angeles, California, this 8th day of December, 1904.

WILLARD C. JAMES.

In presence of—

ARTHUR P. KNIGHT,
TILLIE E. ADAM.
